UNITED STATES PATENT OFFICE.

HERMAN H. KEMPF, OF NEW YORK, N. Y.

TIME SWITCH.

Application filed October 19, 1925. Serial No. 63,396.

My invention relates to automatic time switches and has a particular reference to switches built as a part of an alarm clock and adapted to be set so as to be actuated at a predetermined time.

The object of my invention is to provide a switch of the character above indicated and especially suitable to be used with an automobile clock mounted on the dashboard and adapted to control the automatic lighting of the automobile lamps at a predetermined time. By reversing its action this time switch can be used for turning off the lights in stores and electric signs.

For this purpose I provide a clock of an ordinary construction with a few additional parts so arranged that a trip spring closes a contact at a predetermined time thereby connecting the battery with the lamps which it is desired to light (for instance, a parking lamp or side and tail lamps of an automobile. The contact, thereby closed, will remain closed indefinitely, and the lamps may be then operated manually from an ordinary dashboard switch. The time mechanism may be made operative again by setting the trip spring in tension for which purpose I provide a special lever.

My invention is more clearly described in the accompanying specification and drawing in which—

Figure 1 is a top view of a clock with a portion cut away in order to show my switch mechanism; Figure 2 is a plan view of my switch in an open position; Figure 3 is a plan view of my switch in a closed position; Figure 4 is a side view of the clock looking in the direction of the arrow 4, Figure 2, with my switch mechanism in an open position, and Figure 5 is a side view looking in the direction of the arrow 5, Figure 3, showing the switch closed.

My switch consists of resilient conducting members 1 and 2 adapted to form electrical contact when brought together. These members may be made in the form of copper or bronze flat springs, attached to metal blocks 3 and 4 mounted on an insulating plate 5. This insulating plate or supporting block is attached to the ordinary alarm clock frame plate 6 by means of screws 7.

The blocks 3 and 4 are provided with holes 8 for insulated wires 9 forming a part of the lamp circuit. Thumb screws 10 are provided in the blocks 3 and 4 for clamping the leads 9.

A shaft 12 is rotatively mounted in the

clock frame plates 6 and 11, and is provided with a handle 13 on one end, and a lever 14 on the other. The lever 14 has a pin 15 with an insulating bushing 16 fitted over it. This bushing is adapted to press against the contact spring 2.

The portion of the shaft 12, between plates 6 and 11, is provided with a pin 17 to which one end of a spring 18 is attached. The other end of this spring is fastened to plate 11 by a screw 19. This spring tends to turn shaft 12 to such position that bushing 16 attached to lever 14 is pressed against contacts 1 and 2, thereby closing the electric circuit.

Lever 14 has an aperture 20 near its free end. This aperture is adapted to have the end of a sliding pin 21 project within it, thereby keeping lever 14 in inoperative position, in which position bushing 16 does not close contact springs 1 and 2 as shown in Figure 2. The end of lever 14 is curved outward as shown in Figure 5, so that it can slide over pin 21 and, bending out, snap over the end of the pin with the aperture 20 for holding the lever in inoperative position.

Pin 21 rests with one end against a spring 22 fastened to the plate 11 with a screw 23. Spring 22 is of the type usually found in alarm mechanism. This spring when released will allow pin 21 to come out of engagement with lever 14 (Figures 1, 4 and 5). Bushing 24 is slidably fitted over pin 21 and is fastened with screw 25. Compression spring 26 is placed on pin 21 between plate 6 and bushing 24. This spring normally forces pin 21 against flat spring 22.

Shaft 27, rotatably mounted in plates 6 and 11, carries an index hand 32 at one end for setting the time at which it is desired to have the switch operate. The other end of shaft 27 is provided with a thumb handle 34 for the convenient rotating of said shaft. A pin 34 projects from shaft 27 just back of plate 11. Bushing 28, which carries gear 29 fixed to it, is slidably and rotatably mounted on shaft 27. One end of bushing 28 is provided with a cam surface 33 which is pressed against pin 34 by the action of spring 22. Gear 29 meshes with pinion 36 which in turn meshes with gear 30 of hour hand 31. Gears 29 and 30 are of equal size, so that bushing 28 makes one complete revolution in twelve (12) hours. As cam surface 33 rotates against pin 34, the sudden depression in said surface (usual in alarm mechanism) comes opposite pin 34 permitting bushing 28 to be moved to

the left (Figures 4 and 5) under the action of spring 22, pin 21 following said spring under the action of its compression spring 26. As pin 21 follows compression spring 22, it is withdrawn from the aperture 20 in lever 14, permitting bushing 16 to press contact 2 against contact 1, under the influence of spring 18.

The regular clock mechanism is not shown in order to make the drawing clearer.

The operation of my device is as follows:—

Shaft 27 is turned to a desired position so as to indicate by means of hand 32 a certain hour of the day and its fraction, when it is desired to have the lamps lighted. The ordinary lamp switch is then closed, and handle 13 pushed so as to force the springy end of lever 14 over the end of pin 21, thereby locking the latter in the aperture 20. The contacts 1 and 2 are open with lever 14 in this position, so that the circuit will be interrupted and the lamps not burning, although the main switch is closed (this switch is not shown in the drawing). At a predetermined time, bushing 28 will turn to a position where pin 34 will be located in opposition to the break or depression in cam surface 33. Bushing 28 will then jump under action of the flat spring 22. This spring will follow the bushing and will release the pressure on pin 21 which will slide under action of the spring 26. The end of pin 21 will slide out of aperture 20 of lever 14, thereby releasing the latter. Lever 14 accordingly will turn under the action of spring 18, pressing bushing 16 against contact springs 1 and 2 and closing the circuit through the lamps. Contacts 1 and 2, once closed, will remain closed, and the lamps then can be operated by a regular dashboard switch, while the clock can be used as an ordinary time piece. Whenever it is desired again to have the clock act as a time switch, lever 14 can be set in engagement with pin 21 by rotating shaft 12 by its handle 13.

Important advantages of my clock are that it can be used for automobiles in connection with ordinary lamp switches and can light the lamps at a predetermined time without interference with ordinary manual control of such lamps. The construction is simple and can be easily applied to any ordinary alarm clock, in which case it is only necessary to remove the bell, hammer and to attach a few simple parts as described.

I claim as my invention:

1. Operating means, for an automatic time switch having an alarm clock tripping device, comprising a pin mounted transversely slidably in the clock frames, a shaft rotatably mounted in said frames, a plurality of relatively movable switch elements, a flat resilient switch lever fixed to said shaft near one end of same adapted to rotate with a flat face substantially parallel to one of said frames, said lever adapted when tripped to effect relative

motion between the switch elements for opening or closing an electric circuit therethrough, said lever being suitably formed for locking engagement with the end of said pin, spring means for normally pressing said pin against said alarm tripping device whereby said pin follows same when tripped and releases the lever, said pin projecting when untripped into the path of said lever causing flexure of said lever when it is moved over the end of said pin into locking engagement therewith.

2. Operating means for an automatic time switch having an alarm clock tripping device comprising a pin slidably mounted in the clock frames, a shaft rotatably mounted in said frames, a plurality of relatively movable switch elements, a switch lever fixed to said shaft near one end of same, adapted when tripped to move toward the switch elements for effecting relative motion between said switch elements for opening or closing an electric circuit therethrough, the other end of said shaft being adapted for manual rotation, spring means normally pressing said pin against said alarm tripping device whereby said pin follows same when tripped and releases said switch lever, the switch lever having an aperture through which said pin, when untripped, is adapted to pass when said shaft is manually turned for locking said lever away from the switch elements.

3. In an automatic time switch, a clock mechanism having an alarm tripping device, a pair of spaced resilient contact members or switch elements insulatively mounted on a frame of the clock mechanism, a shaft rotatably mounted in said frame, a switch lever fixed near the end of said shaft, said switch lever adapted to rotate substantially parallel to said frame, the rotation of said lever being to and from said switch elements for controlling the spacing between them and thereby the circuit therethrough, spring means for normally rotating said lever toward said elements, a pin transversely slidable in said frame, said lever being suitably formed for locking engagement away from the switch elements with the end of said pin, spring means for normally pressing said pin against said alarm tripping device whereby said pin follows same when tripped and is withdrawn thereby from engagement with said lever.

4. Operating means for an automatic time switch having a plurality of relatively movable switch elements, an alarm clock tripping device comprising a pin mounted transversely slidably in the clock frames, a shaft rotatably mounted in the clock frames, a switch lever fixed to said shaft at the rear of the rear clock frame adapted when tripped to effect relative motion between each other of the switch elements for opening or closing an electric circuit therethrough, said lever being suitably formed for locking engagement with the end of said pin, a handle fastened to the

other end of said shaft near the front clock face, said handle projecting outwardly beyond the sides of the clock, spring means normally pressing said pin against said alarm 5 tripping device whereby said pin follows same when tripped and releases the lever, said pin projecting to the rear of the rear frame, when untripped, into the path of said lever, being adapted thereby for locking engagement with 10 said lever when manually turned away from the switch elements.

5. In an automatic time switch, a clock mechanism having an alarm tripping device, a plurality of switch elements, a shaft rotatably mounted in the clock frames, a switch lever fixed to said shaft, said switch lever being normally spring actuated to rotate substantially parallel to the clock frames towards 15 said switch elements, the rotation of said 20 lever to and from said switch elements controlling the circuit between them, a pin transversely movable in said frames, said lever, when manually rotated away from the switch elements, being suitably formed for locking 25 engagement with said pin, spring means for normally pressing said pin against said alarm tripping device whereby said pin follows same when tripped and is withdrawn there-

by from engagement with said lever, and a handle fastened to said shaft near the front 30 clock face for manually rotating said lever away from the switch elements, said handle projecting outwardly beyond the side of the clock.

6. In an automatic time switch, a clock 35 mechanism having an alarm tripping device, a plurality of switch elements, a shaft rotatably mounted in a frame of the clock, a switch lever fixed to said shaft, said switch lever being normally spring actuated to rotate substantially parallel to said frame towards said 40 switch elements, the relative position between said lever and the switch elements controlling the circuit through the latter, a pin transversely movable in the clock frame, said 45 lever, when rotated away from the switch elements, being suitably formed for locking engagement with said pin, spring means for normally pressing said pin against said alarm tripping device whereby said pin follows 50 same when tripped and is released thereby from engagement with said lever.

Signed at 318 Broadway, New York, in the county of New York and State of N. Y. this 15th day of October, A. D. 1925.
